US00D479638S

(12) **United States Design Patent** (10) Patent No.: **US D479,638 S**
Didion (45) Date of Patent: ** Sep. 9, 2003

(54) **STABILIZER**

(75) Inventor: **Michael S. Didion**, St. Peters, MO (US)

(73) Assignee: **Precision Components & Assemblies, Inc.**, St. Peters, MO (US)

(**) Term: **14 Years**

(21) Appl. No.: **29/161,893**

(22) Filed: **Jun. 6, 2002**

(51) LOC (7) Cl. **09-08**

(52) U.S. Cl. **D34/38**

(58) Field of Search D34/29, 35; 198/831, 198/494, 497, 866, 837, 755, 752.1, 850, 852, 853; D8/395, 396, 499
